UNITED STATES PATENT OFFICE.

CHARLES CARROLL STEWART, OF PHILADELPHIA, PENNSYLVANIA,
ASSIGNOR OF ONE-HALF TO ARCHIBALD T. JAMES, OF PHILA-
DELPHIA, PENNSYLVANIA.

CARPET FABRIC.

No. 824,045.

Specification of Letters Patent.

Patented June 19, 1906.

Application filed March 8, 1906. Serial No. 249,127.

To all whom it may concern:

Be it known that I, CHARLES CARROLL STEWART, a citizen of the United States, residing at Philadelphia, in the county of Philadelphia and State of Pennsylvania, have invented certain new and useful Improvements in Carpet Fabrics; and I do hereby declare the following to be a full, clear, and exact description of the invention, such as will enable others skilled in the art to which it appertains to make and use the same.

My invention relates to improvements in carpet fabrics.

In manufacturing the product of my Patent No. 762,210, of June 7, 1904, wherein I introduced a soft cushioning-warp above the ordinary back or stuffer warps, below the pile and between the upper and lower wefts it has been found that these large cushioning-warps resting immediately upon several of the smaller backing-warps have the tendency to mix with said backing-warps as they go through the loom, and thus drop down between said latter warps at intervals, so that streaks of white appear on the back of the finished carpet. The result of this dropping or falling of the cushioning-warps is to render the surface of the carpet more or less irregular, and at each point where such a warp-thread has fallen or wedged itself between the backing-warps the cushioning effect is lost to a large degree. To remedy this defect and prevent the cushioning-warps from thus dropping down between the backing-warps is the object of this invention, and to accomplish this result I provide an additional and intermediate weft-thread running between the ordinary upper and lower wefts and transversely between the backing and cushioning warps. This intermediate weft-thread is thrown by an extra shuttle or other suitable feeding device on the loom provided for that purpose. It passes across between the cushioning-warps and backing-warps and comes back below the backing side by side with the ordinary lower weft and is bound in by the binding-warps.

In the accompanying drawings, illustrating the preferred embodiment of my invention, Figure 1 is an enlarged sectional view of a piece of carpet made in accordance with my invention, the section being taken in a

line with the warps. Fig. 2 is a sectional view taken in a line with the wefts. Fig. 3 is a perspective view of a portion of a strip of velvet carpet looking at a crosscut edge. Fig. 4 is a similar view with the threads partly raveled out to show the thickness of the cushioning-warps when expanded as compared with that of the backing-warps and pile.

While the preferred embodiment of my invention is illustrated in the accompanying drawings and its construction and arrangements of parts are described in this specification, the right is reserved to make such changes from the construction shown and described herein as the scope of the claims here-to appended will permit.

Referring more particularly to the drawings, 1 represents the backing-warps; 2, 3, the binding-warps, respectively; 4, the cushioning-warps; 5 and 6, the ordinary upper and lower weft-threads, respectively; 7, the pile, 75 and 8 and 9, respectively, the additional intermediate and lower wefts. As shown in the drawings, said additional weft-thread passes between the backing and cushioning warps, fixing each in place and preventing them from mixing and comes back, as at 9, below said backing alongside of the lower weft-thread 6. These additional wefts are bound into place by the binding-warps, and they insure the arrangement of a cushioning-warps below each row of pile or yarn.

In Figs. 3 and 4 I have attempted to give some idea of the cushioning effect given by my interlining by showing it compressed as it is woven into the carpet and as expanded 90 when raveled out. With the addition of the extra wefts described herein, whereby the cushioning-warps are prevented from becoming mixed with the backing-warps, which is the only objectionable feature of the product 95 of my former patent, hereinbefore referred to, it will be seen that the present product is a great improvement over the ordinary carpets in softness, appearance, and wearing qualities.

While the extra weft-threads which separate the backing or stuffer warps and the cushioning-warps are described and shown as passing below the backing side by side with the lower wefts on the return stroke, they 105 may also be returned above said backing-

warps. Said extra weft may also be re-turned above the cushioning-warps and below the pile side by side with the upper wefts, if desired.

5 The machine for making my improved carpet should be provided with additional harness and shuttles to operate the additional weft-thread.

Having thus described my invention, what 10 I claim as new, and desire to secure by Letters Patent, is—

1. In a carpet fabric, the combination with binding warp-threads, upper and lower weft-threads, backing or stuffer warps, pile and cushioning-warps arranged between said stuffer-warps and said pile, of means for separating said cushioning-warps and stuffer-warps.

2. In a carpet fabric, the combination with 20 binding warp-threads, upper and lower weft-threads, backing or stuffer warps, pile and cushioning-warps arranged between said stuffer-warps and said pile, of means running between said cushioning-warps and stuffer-warps for separating said stuffer-warps and cushioning-warps.

3. In a carpet fabric, the combination with 30 binding warp-threads, upper and lower weft-threads, backing or stuffer warps, pile and cushioning-warps arranged between said stuffer-warps and said pile, of means for separating said cushioning-warps and said stuffer-warps and for retaining each in a separate plane.

35 4. In a carpet fabric, the combination with

binding warp-threads, upper and lower weft-threads, backing or stuffer warps, pile and cushioning-warps arranged between said stuffer-warps and said pile, of means for preventing the cushioning-warps from entering 40 the plane of the stuffer-warps.

5. In a carpet fabric, the combination with binding warp-threads, upper and lower weft-threads, backing or stuffer warps, pile and cushioning-warps arranged between said 45 stuffer-warps and said pile, of an additional weft-thread arranged between said stuffer-warps and cushioning-warps.

6. In a carpet fabric, the combination with binding warp-threads, upper and lower weft-threads, backing or stuffer warps, pile and cushioning-warps arranged between said 50 stuffer-warps and said pile, of an additional weft-thread run below said cushioning-warps and above said stuffer-warps.

7. In a carpet fabric, the combination with binding warp-threads, upper and lower weft-threads, backing or stuffer warps, pile and cushioning-warps arranged between said 55 stuffer-warps and said pile, of additional weft-threads run through between said stuffer-warps and cushioning-warps and back below said backing-warps beside the lower weft-threads.

In testimony whereof I affix my signature 60 in presence of two witnesses.

CHARLES CARROLL STEWART.
